(No Model.)

F. LOGAN.

APPARATUS FOR MANUFACTURING GAS.

No. 582,655.

Patented May 18, 1897.

UNITED STATES PATENT OFFICE.

FERDINAND LOGAN, OF PHOENIXVILLE, PENNSYLVANIA.

APPARATUS FOR MANUFACTURING GAS.

SPECIFICATION forming part of Letters Patent No. 582,655, dated May 18, 1897.

Application filed May 8, 1896. Serial No. 590,687. (No model.)

To all whom it may concern:

Be it known that I, FERDINAND LOGAN, of Phoenixville, Pennsylvania, have invented a certain Improvement in Apparatus for Manufacturing Gas, of which the following is a full, clear, and exact specification.

My invention relates to certain improvements in the manufacture of gas, and has for its object to manufacture at a minimum price a gas of high illuminating power from a liquid hydrocarbon and steam, the plant being principally designed for use where a comparatively small quantity of gas is to be manufactured and used, as for a private consumer, although by increasing the size and capacity of the apparatus it may be employed for the manufacture of gas upon a commercial scale.

In the accompanying drawings, Figure 1 is a sectional elevation of an apparatus constructed in accordance with my invention; and Fig. 2 is a transverse sectional elevation of the same on the line 2 2, Fig. 1.

Referring to the drawings, A represents the outer shell or casing of a boiler provided with an inner combustion-chamber B, a continuous water-chamber a being formed between the walls of the combustion-chamber and the outer shell or casing, so that the greatest efficiency may be obtained from the fuel. Within the combustion-chamber are suitably arranged grate-bars b, beneath which is an ash-pit b', having an outlet-pipe C for the escape of the manufactured gas.

Above the shell or casing A is a cylindrical vessel D, the lower wall of which forms the upper line of the combustion-chamber, the upper chamber being separated from the water-chamber by a separating plate or ring d.

Extending vertically within the cylindrical vessel D are a series of vertical tubes e, secured to upper and lower tube-sheets, the upper tube-sheet e' forming the lower portion of a smoke box or chamber g, which forms a flue having a centrally-arranged outlet h for the escape of the products of combustion, and being also provided with a series of manholes i, arranged around the central opening, for the purpose of cleaning the tubes when necessary. From the top of the smoke-box extends a stack L, through which the products of combustion escape, and a similar stack M is arranged above an outlet a' in the shell or

casing A for the escape of the products of combustion directly from the combustion-chamber B.

The cylindrical vessel D is filled with hydrocarbon, which as it is volatilized by the heat from the products of combustion escaping through the tubes e accumulates in the form of an oil-gas until it is conducted to the fixing-chamber, the degree of heat to which the oil is subjected being governed by a valve m, arranged above the escape-flue a', leading directly from the combustion-chamber, and by a valve l, provided above the top of the vessel D, the two valves being so arranged that either one or other, or both, may be opened to direct the escape of the products of combustion through the flue a' to heat the water and fire-brick, or through the tubes e to heat the oil, or partially through both escape-flues, if desired.

In the combustion-chamber B is an arch N, formed of perforated fire-brick and extending continuously from end to end of the chamber, the perforations n in the arch serving for the escape of the products of combustion through either of the escape-flues, and above this arch the combustion-chamber is filled with checker-work fire-brick, which is heated by the products of combustion before the final escape through the flues, the height of the combustion-chamber being sufficient to provide a depth of checker-work sufficient to fix the gas.

On the shell D is a gage-glass p and a suitable pressure-gage and petcocks, and the water-chamber is provided with similar devices for the purpose of determining the height of liquid and the pressure of vapor in the vessels.

Extending from the upper portion of the shell A of the combustion-chamber is a pipe s, provided with a safety-valve s' of any ordinary construction, and leading from this pipe is a second pipe T, extending through the upper portion of the casing A into the interior of the combustion-chamber at a point above the arch N.

From the upper portion of the cylindrical vessel D leads a pipe t, connected to a vertical pipe t', also provided with a safety-valve, the lower end of the pipe t' being connected to the pipe T, which leads to the combustion-

chamber, the pipes $s' t'$ being provided with valves $w w'$, respectively, to govern the flow of steam and oil vapor into the combustion-chamber.

5 Within the combustion-chamber B, at a point above the level of the grate-bars, is an arch N, of fire-brick, which is heated by the products of combustion, as previously described.

10 In operation the chamber or boiler a is filled with water to a proper level, and the oil-chamber D is filled with a suitable hydro-carbon, and the fire is started on the grate-bars, the combustion being preferably aided 15 by a forced air-blast through the pipe C' under the grate-bars. All valves being closed, the valve m , leading to stack M, is opened, and the heat acts directly on the water-chamber without passing up through the tubes in 20 the oil-chamber. After a short time the steam is raised to the proper pressure and temperature, and the arched fire-brick and checker-work are intensely heated. The valve m is then closed and the valve l is 25 opened, the products of combustion then passing up through the tubes e in the oil-chamber, heating and vaporizing the oil until it reaches a temperature sufficiently high for the purpose intended, or after the products 30 of combustion have been directed for a short time through the escape-flue of the boiler-section they may then be partially directed through the escape-flues of the boiler-section and partially through the escape-flue of the 35 oil-chamber D and the subsequent heating of the water, the oil, and the fire-brick be carried on simultaneously. When the oil and water have been heated, the fire-brick and checker-work have reached the proper 40 temperature, and the process of manufacturing the gas can then be commenced.

The escape-pipe C from the bottom of the ash-pit is opened, and if an oil-gas is to be manufactured the valve w' in the pipe t' is 45 opened, and the oil-vapor, under a high pressure and temperature, is forced down through the pipe t' into the combustion-chamber and, passing through the heated fire-brick and the incandescent fuel which remains on the grate-bars, is fixed and issues from the pipe C as a 50 permanent fixed gas. In practice, however, it is not altogether advisable to force the oil-vapor down through the mass of incandescent fuel, and it is preferably diluted to some extent by opening the valve w and admitting 55 with the oil-vapor a quantity of steam sufficient for the purpose, the vapors of steam and oil mingling in the pipe T and passing through said pipe into the combustion-chamber and the steam in the fixing operation operating to some extent to smother the oil-vapor and prevent its flashing into lampblack. The steam in passing through the heated fire-brick and incandescent fuel is decomposed 60 and, combining partly with the carbon of the fuel and partly with the carbon of the oil-vapor, forms a water-gas, the whole body of gas 65

so formed escaping through the pipe C as a mixture of oil-gas, carbonic oxid, and free hydrogen.

70 In the manufacture of a water-gas the supply of oil-vapor may be cut off altogether and the steam admitted alone or in combination with a small percentage of the oil-vapor, and in this way by burning a gas-jet at the exit 75 end of the apparatus or the holder the purity of the gas and its illuminating qualities may be observed and the candle-power be increased or diminished, as desired, by increasing the supply of oil-vapor or the supply of 80 steam, as may be desired.

The apparatus as described is of the alternating class—that is to say, one in which the blowing up of heats alternates with the production of gas, it being impracticable to 85 carry on the process of manufacturing gas continuously. If, however, it is desired to employ a continuous process with the same or practically the same apparatus, a retort is 90 substituted for the fire-brick in the combustion-chamber, and the gas or steam, or both, is forced into the retort and escapes from the opposite end thereof as a fixed gas, the continuous fire in the combustion-chamber heating up the retort and at the same time 95 keeping up the pressure of steam and of oil-vapor without otherwise affecting the operation, it being then possible to keep both escape-valves open and to permit the products of combustion to act at the same time on the 100 oil and water chambers.

Having thus described my invention, what I claim, and desire to secure by Letters Patent, is—

1. An apparatus for the manufacture of 105 gas, comprising in combination, a combustion-chamber, checker-work fire-brick contained therein, water-legs forming the steam-boiler surrounding the combustion-chamber, a chamber containing oil mounted above said 110 combustion-chamber, escape-flues for the products of combustion in said oil-chamber, and valved outlets for directing the passage of the products of combustion either directly 115 from the combustion-chamber or through the flues of the oil-chamber.

2. The combination of the combustion-chamber, a steam-boiler surrounding the same, a valved escape-flue leading directly from said combustion-chamber, a gas-outlet 120 beneath the grate-bars of the combustion-chamber, a mass of checker-work fire-brick in the combustion-chamber, an oil-chamber, escape-flues therein, and a valved outlet at the top of the oil-chamber for directing the 125 passage of the products of combustion through the flues of said oil-chamber, substantially as specified.

3. An apparatus for manufacturing gas, comprising in combination, a combustion-chamber B, a steam-boiler A, partially surrounding the combustion-chamber, an oil-containing chamber D above the combustion-chamber, escape-flues for the products of 130

5 combustion in said oil-chamber, valved outlets *a'* and *h*, for directing the passage of the products of combustion either directly from the combustion-chamber or through the flues of the oil-chamber or partly through both outlets, vapor-pipes connecting the oil-chamber and the steam-boiler with the interior of the combustion-chamber, and an exit-pipe *C* for the manufactured gas provided in said com-

bustion-chamber at a point below the grate-bars, substantially as specified.

In testimony whereof I have hereunto set my hand, this 22d day of April, A. D. 1896, in the presence of two subscribing witnesses.
